UNITED STATES PATENT OFFICE.

BERNHARD FISCHER, OF DRESDEN, GERMANY.

GRINDING APPARATUS.

1,101,171.

Specification of Letters Patent. Patented June 23, 1914.

Application filed December 11, 1913. Serial No. 805,935.

To all whom it may concern:

Be it known that I, BERNHARD FISCHER, engineer, a subject of the King of Saxony, and resident of Hohestrasse 79, Dresden, 5 Kingdom of Saxony, German Empire, have invented new and useful Improvements in Grinding Apparatus, of which the following is a specification.

The present invention has for its object a 10 grinding apparatus provided with means for conducting away by sucking action the dust generated during the grinding operation.

According to the present invention, the 15 grinding apparatus, the grinding wheel or ring of which is provided in a well-known manner with fan-blades for sucking in the dust generated, is inclosed within a casing surrounding the said fan-blades and the 20 grinding-wheel and such casing is provided with a vertically arranged sucking slit and a perforated water pipe or sprinkler, a dish or cup collecting the liquid used in the grinding operation and a free air-discharge for 25 sucking away and settling the dust generated and for maintaining a purified atmosphere within the workroom. The sucking slit is formed by a vertically adjustable work-table and the outer edge of the grinding-wheel, and the water pipe or sprinkler, 30 the liquid collecting dish supplying the water to the pipe or sprinkler mentioned and the free air-discharge situated above said collecting dish or cup act together or in combination with each other in such a manner 35 that the dust sucked in and sufficiently saturated with water is compelled to partially settle at the bottom of the surrounding casing whereas the water mixed with dust is fed 40 into the collecting dish or cup and the air relieved from dust is returned back into the work-room in which other machines or tools are mounted.

A grinding-apparatus arranged according 45 to the present invention has, in comparison with known grinding-apparatus, the advantage that the fan mounted up to now separately at a suitable distance from the machine and the long pipe-system between 50 the said fan and the machine may be dispensed with and the power formerly necessary for driving the fan can be reduced to a very great degree. Furthermore, a grinding-apparatus combined with a fan may be 55 mounted or arranged in any suitable place of the work-room and the apparatus may be

operated with a horizontally or vertically rotating grinding-wheel or ring. In case of a horizontally rotating grinding-disk, the work-table is provided with a rim or edge 60 forming a continued part of the sucking casing. Said rim outwardly surrounds the slit for sucking the air and may be vertically adjusted in the manner of a telescope within the casing and in correspondence with the 65 wear and tear of the upper surface of the grinding-wheel or ring. In this manner the outer edge of the slit may always be properly adjusted in a level with the inner edge of said slit. A dressing-apparatus may be 70 arranged above the grinding-wheel in such a manner that the dust generated during the dressing of the grinding-wheel may directly be forced into the casing surrounding said wheel.

In the accompanying drawing Figure 1 is a sectional longitudinal view according to line A B of Fig. 2 of a grinding-apparatus embodying my improvements. Fig. 2 is a plan-view and a horizontal section according to line C D of Fig. 1 of my apparatus.

In the construction shown of the grinding-apparatus the grinding-wheel is arranged to rotate horizontally.

1 is a grinding-wheel or ring and 2 a disk supporting said grinding-wheel. A cylindrical part 4 inclosing or surrounding the spindle 3 of the apparatus projects in a downward direction from the lower surface of the disk.

5 is a series of blades arranged on the periphery of the cylindrical part 4 and partaking of the rotary movement of the grinding-wheel 1, thus acting like the blades of a fan.

6 is a casing surrounding or inclosing the grinding-wheel 1 and the fan-blades 5 and reaching with half its part situated below the working-place 7 nearly up to the height of the disk 2. The other half of this casing projects for a short length above 100 the grinding-wheel 1 and is covered by a semicircular plate or disk 8 serving as a protecting-shield and a delivery-table.

9 is a perforated water-pipe or sprinkler capable of being shut off and projecting into the casing 6 below the fan-blades 5. Said water-pipe or sprinkler is supplied with water by a pump 10 or in any other suitable manner. A pipe 9* connects the water-pipe or sprinkler 9 with the pump 10 105 which is driven by a belt or band-pulley 11, the belt or band of which runs around

the pulley 12 of smaller diameter and fastened to the shaft 13 of the pulleys 14, 15 for driving the pulley 16 fastened to the main shaft 3 of the apparatus. The rotary movement of the pulleys 14, 15 is derived in any convenient manner from a source of power not shown in the drawing.

A hollow space or slit 17 is formed between the inner rim of the casing 6 and the outer rim of the grinding-wheel 1. During the rotary movement of this grinding-wheel the fan-blades 5 suck in the air and simultaneously the dust generated during the grinding-operation. The dust generated is thrown into the hollow space or slit 17 also by means of the grinding-wheel 1 itself. In this manner, the water-pipe or sprinkler 9 moistens the dust-air sucked in so that the wet dust particles contained in it settle at the bottom of the casing 6 from which the water collected in the latter flows into the bed-plate 18 of the apparatus formed as a collecting cup, whereas the air sucked in enters into a pipe or passage 19 tangentially connected to the casing 6. In this manner, the said air may directly escape through the mouth 20 of the pipe or passage 19 into the work-room.

Any water and dust particles taken along by the air will fall down into a vessel 21 arranged below the mouth 20 of the air discharge 19, said vessel being connected to the bed-plate 18. The wet dust-particles carried along will settle in this vessel by their gravity. The bed-plate mentioned may be provided with ribs of different height, over which the collected water flows for being purified in such a manner that it will enter into the sucking-pipe 22 of the pump 10 in a nearly purified state and returned or supplied through the conduit or pipe 9* into the perforated water-pipe or sprinkler 9. By this means it will only be necessary to add fresh water once a day for replacing the water entering into the atmosphere in the shape of water-dust.

To keep the level of the sucking slit 17 and of the space within the casing 6 near the working-place 7 surrounded by the lower part of the casing-wall, in correspondence with the wear and tear of the grinding surface 1, the working-table 23 which may be adjusted in height by an automatically stopping worm-gear, is provided on its lower surface with a downwardly projecting edge or rim 24. This edge or rim will telescopically enter into the casing 6 in such a manner that the air will be sucked in by the slit formed between the working-table 23 and the grinding-wheel 1.

The automatically stopping worm-gear mentioned consists of two worm-wheels 25, 26, the hubs of which are formed as nuts which are engaged by the screws of two long screw-bolts 29, 30 projecting in a down-

ward direction from the lower surface of the working-table 23. The worm-wheels 25, 26 are supported by the plumber-blocks 27, 28, projecting in an upward direction from the bed-plate 18 of the grinding-apparatus. These worm-wheels 25, 26 are in gear with two worms 32, 33 fastened to the shaft 31 horizontally supported on the bed-plate 18 in such a manner that the worm-wheels 25, 26 are rotated on the rotary movement of the shaft mentioned by means of the hand-wheel 34. The hubs of said worm-wheels act as nuts and cause an upward or downward movement of the screw-bolts 29, 30 and together with said movement the adjustment of the work-table 23.

A traverse or bar 37 arranged above the grinding-wheel 1 is fastened to the lateral posts 35, 36. A dressing-apparatus 38 is permanently mounted on said traverse or bar in such a manner that the dust generated during the dressing of the grinding-wheel 1 is compelled to directly enter into the casing 6 acting together with the blades 5 as a fan.

I claim as my invention:

1. In a grinding-apparatus the combination with a rotating grinding-wheel, of means for sucking in the dust generated on said grinding-wheel, means for settling the dust generated, a work-table for feeding the work in hand to the grinding-wheel, and means for vertically adjusting the table.

2. In a grinding-apparatus, the combination with a rotating grinding-wheel, of means for sucking in the dust generated on said grinding-wheel, means for settling the dust generated, a work-table for feeding the work in hand to the grinding-wheel, an edge or rim provided on the lower surface of the work-table and adjustably arranged together with the latter for almost completely inclosing against the surrounding atmosphere the said means for sucking and settling the dust generated, and means for vertically adjusting the said work-table.

3. In a grinding-apparatus, the combination with a rotating grinding-wheel, of means for sucking in the dust generated on said wheel, a liquid sprinkling means for settling the dust generated, a work-table only partially inclosing the periphery of the grinding-wheel and used for feeding the work in hand to the grinding-wheel, an edge or rim provided on the lower surface of the work-table and telescopically adjustable within the casing of the apparatus for almost inclosing the said means for sucking in and settling the dust generated, there being a space provided between the work-table and the grinding-wheel through which passes the air from outside necessary for sucking in the dust, means for vertically adjusting the work-table, means for collecting the liquid and settling the dust after being

ing separated from the air, and means for returning said liquid to the said sprinkling means.

4. In a grinding-apparatus, the combination with a rotating grinding-wheel, of a series of fan-blades rotating together with said wheel and used for sucking in fresh air into the apparatus and for removing the dust generated on the grinding-wheel, a 10 perforated water-pipe or sprinkler for the supply of liquid to settle the dust generated, a work-table only partially inclosing the periphery of the grinding-wheel for feeding the work in hand to the grinding-wheel, an 15 edge or rim arranged on the lower surface of the work-table and telescopically adjustable within the apparatus, a stationary casing for almost completely inclosing the fan-blades and the perforated water-pipe or 20 sprinkler, there being a passage provided in the stationary casing for discharging the

air mixed with liquid and dust, a settling-vessel situated below said passage, there being a space arranged between the work-table and the grinding-wheel for sucking the 25 air from outside into the apparatus, a collecting cup for the reception and supplemental purification of the liquid separated from the air and dust, prior to returning this liquid to the perforated water-pipe or 30 sprinkler, and a pump connected to a pipe system for returning the liquid, freed from dust and air, to the perforated water-pipe or sprinkler.

In testimony, that I claim the foregoing 35 as my invention, I have signed my name in presence of two witnesses, this 26th day of November, 1913.

BERNHARD FISCHER.
